UNITED STATES PATENT OFFICE

SIDNEY A. REEVE, OF ORANGETOWN, NEW YORK, ASSIGNOR TO BELOIT IRON WORKS,
OF BELOIT, WISCONSIN, A CORPORATION OF WISCONSIN

PAPER DRIER

Application filed March 17, 1930. Serial No. 436,307.

This invention relates to a paper machine and more particularly to a paper machine wherein both the wet and dry ends of the machine are totally enclosed within a substantially air-tight housing or casing to permit the substantial exclusion of air from within the casing and permit the effecting of a considerable economy of heat in the drying operation.

10 The art of drying paper as heretofore practiced may logically be divided into three classifications; (1) drying under purely atmospheric conditions without the application of artificial heat; (2) drying paper in an 15 open type drier by contact between the wet web of paper and traveling heated surfaces, such as drier drums, and (3) drying paper in a totally enclosed drier unit under vacuum.

The purely atmospheric type of drier 20 wherein no artificial heat is employed would obviously require a tremendous amount of space in which to complete the drying of the paper, or if unheated rolls were employed for supporting the paper web during the air 25 drying operation, a very large number of such rolls would be necessary to take care of the output of an ordinary present day paper machine.

The use of the steam heated, unenclosed 30 drier, as compared with the purely atmospheric type of drier, would permit a considerable diminution in the number of drier drums required but the fuel efficiency of the open type of steam drier drum drier unit is 35 relatively low owing to the fact that heat is expended not only in evaporating moisture from the paper web but also in heating the surrounding air. Thus in this type of drier, the size of drier unit is reduced at the expense of fuel cost.

In the third type of drier, wherein the 40 drying operation is carried out in an enclosed chamber under vacuum, a reduction both in the size of the drier unit, i. e. in the area of 45 drying surface, and in the fuel cost is effected, the latter because of the fact that the heat supplied is utilized entirely in the evaporation of the moisture in the paper and there is no loss because of unnecessary heating 50 of air. However, the construction cost

of this type of drier is relatively high due to the necessity of an air-tight casing and seals, vacuum pumps and the like. Furthermore, although a considerable saving in fuel is effected using this vacuum type of drier, as compared with the steam heated, unenclosed type, it is nevertheless evident that, since all of the water in the paper is evaporated entirely by means of applied heat, the fuel economy is not great as should be theoretically possible, as will later be evident from a consideration of my invention as hereinafter described.

While the development of the paper drier through these three classes or stages represents a very marked progress in the art of drying paper, it is nevertheless pointed out that such progress has been undertaken with reduction in the size of equipment as its main aim and with fuel economy as a secondary gain and without a full recognition of the further possibility for substantial additional saving in fuel both for heating and power purposes, provided the desideratum of size and first cost of construction be abandoned.

In other words, reviewing past progress in paper drying through the three steps just outlined, in passing from the first to the second step, the speed of the drying operation was greatly increased with a reduction in the size of drier equipment but this was done at the cost of increasing fuel consumption from nothing at all to a third or so more than that required theoretically to evaporate the moisture in the paper. In passing from the second stage to the third, the gain has again been primarily in smaller size of drier equipment with an incidental reduction of fuel consumption back to about 100% of that theoretically required for directly evaporating the moisture in the paper.

The present invention contemplates sacrificing somewhat initial cost of construction and size of paper machine in order to obtain greater fuel efficiency. In order to do this I make use of the principle of multiple effect evaporation, a principle which to the best of my knowledge has never heretofore been applied to the drying of paper. I furthermore

utilize the cooler atmosphere at the wet end of the paper machine, the showers, and the like, for condensing a portion of the steam generated from the moisture in the paper web during the drying operation, at the same time effecting a heat interchange between such steam or water vapor and the paper stock on the forming part of the machine. To best accomplish these ends, I provide a 10 paper machine that is wholly enclosed within a casing divided into compartments. In these compartments, contrasted degrees of pressures may be obtained with substantial exclusion of air or air may be admitted to one or 15 more compartments with the provision of a heat interchanging air regenerator for utilizing the heat of the air within the casing to preheat the air admitted to the casing.

It is accordingly an object of the present 20 invention to provide a paper machine that is entirely enclosed and that is divided into different sections or compartments which may be operated under contrasted conditions of pressure to obtain the advantages of multiple effect evaporation.

It is a further important object of this invention to provide an enclosed sectional drier from which air is substantially excluded and in which steam generated from the moisture 30 contained in the paper web in one section is utilized in the drying or heating element of another section, whereby a great economy in heat consumption for effecting the drying of the paper may be realized.

It is a further important object of this 35 invention to provide as one section of the enclosed drier unit, high pressure steam coils in place of the usual drier drums.

It is a further important object of this 40 invention to provide a paper machine and housing therefor enclosing the entire machine and means for drawing steam generated from the moisture in the paper as it traverses a portion of the driers towards the extreme 45 wet end of the machine to effect a substantial condensation thereof and the heat interchange between such steam and the paper stock on the forming portion of the machine.

It is a further object of this invention to 50 save fuel by enclosing all or a part of the drier drums in a substantially air-tight casing, not subjected to vacuum, through which air is circulated, the heat abstracted therefrom being utilized to preheat the incoming air, instead of to evaporate moisture in drier compartments of lower pressure.

Other and further important objects of this 55 invention will be apparent from the disclosures in the specification and the accompanying drawings.

This invention (in a preferred form) is illustrated in the drawings and hereinafter more fully described.

On the drawings:

The drawings as a whole represent diagrammatically an entire paper machine embodying the various features of my invention.

Figure 1 is a side elevational view, with 70 the side of the casing removed, of a fourdrinier forming part of a paper machine embodying my invention.

Figure 2 is a continuation of Figure 1 showing the presses, the details of which form 75 no part of my invention but this figure is included to show a continuous machine.

Figures 3 and 4 are similar continuations 80 of Figures 1 and 2 showing intermediate drier sections.

Figure 5 is a side elevational view of a drier section containing high pressure steam coils.

Figure 6 is a continuation of Figure 5 showing the end of the drier unit and calender 85 stack.

Figure 7 is a side elevational view of a modified form of the drier compartment shown in Figure 6.

As shown on the drawings:

The reference numeral 1 indicates as a whole a Fourdrinier paper making machine which is, in accordance with my invention, entirely enclosed within a housing or casing 2. The paper machine 1 comprises the usual main sections of a machine of this type, viz., a fourdrinier 3, presses 4 and a drier 5. All of these sections are included within the main casing 2, which is itself preferably divided into separate sections or compartments: compartment A including the forming part 3, the press part 4 and a portion of the drier drums of the drier part 5; a compartment B constituting the middle drier section; compartment C housing high pressure steam coils 6; and compartment D constituting an equalizing chamber from which the paper passes off of the paper machine to a calender stack 7. It will be understood that the division of the paper machine housing into compartments is a more or less arbitrary one and that fewer or more compartments may be provided.

The forming portion of the paper machine, which is supported from a flooring 9, may be of a conventional type, including a head box 10, a Fourdrinier table structure 11, flat stationary suction boxes 12 and a suction couch roll 13. A forming wire 14 is trained in the usual manner around a breast roll 15, over table rolls 16, the flat boxes 12 and around the suction couch roll 13, the under or lower run of the wire being supported by various idler and tension rolls 17.

In accordance with my invention, stock is admitted into the head box 10 of the paper machine through a piping 18, in which is provided a valve 19 and a loop or sinuous bend 20, both of which serve to control and throttle down the flow of stock to the head box 10.

The entire compartment A in which is housed the forming part 1, press part 4 and portion 5 of the drum driers, is maintained under a suitable vacuum, preferably as high as can 5 be practically maintained. It is for this reason that the valve 19 and serpentine pipe 20 are provided, in order that the stock flowing to the machine may be throttled sufficiently to maintain fair constancy of flow in the face 10 of possible variations in the vacuum within the compartment A. The serpentine pipe 20 is preferably arranged horizontally, but is shown here as vertically arranged for convenience in depiction. From the head box 15 10, the stock flows over a suitable apron 21 onto the forming wire 14 and in passing over the table rolls 16 and suction boxes 12 and suction couch roll 13, water is extracted from the stock to form the moist web of paper, 20 indicated by the reference numeral 22. The white water collecting under the table rolls 16 in a save-all 23 is discharged through a pipe 24 leading into a white water pump (not shown), positioned in the basement. 25 Vacuum is maintained within the casing A by means of one or more suction pumps 100 having a branched intake 101 connected to the flat boxes by means of pipes 27 and 28 and to the suction chamber of the couch roll 33 13 by a pipe 29. Said intake of the pump 100 is likewise connected by a pipe 30 through an automatic reducing valve 31 to the upper extreme end of the casing 2. The reducing valve 31 in the pipe 30 is set to impose a small 35 difference in pressure between the interior of the suction boxes 12 and of the suction chamber within the couch roll 13, on the one hand, and the interior of the compartment A. Because of this difference being but slight, the 40 suction boxes may be given a larger area than usual. The vacuum pump 100 connected to the pipes 27, 28, 29 and 30 may be regarded as the equivalent of the vacuum pump forming a part of all Fourdrinier machines, being 45 merely somewhat larger for the attainment of a higher vacuum, but not absorbing necessarily much more power.

Inasmuch as compartment A includes a number of steam heated drier drums 33, there 50 is, of course, a considerable amount of steam or water vapor formed within this compartment from the moisture in the heated web of paper and as all of this water vapor is drawn to the wet end of the compartment A by 55 virtue of the suction created within the pipes 27, 28, 29 and 30, a considerable amount of condensation takes place as the steam or water vapor passes into the cooler portion of the compartment A and contacts the stock and various showers in the press part 4 and forming part 1. To aid in removing the condensed water and to further insure condensation of the water vapor from the air removed from compartment A, a partition or baffle 34 is provided above the head box 10 extending

width of the casing and a plurality of conduits 103 are arranged to pass through the head box 10 to connect the underneath portion of the Fourdrinier section with the part of the compartment immediately adjacent the pipe 30. In this way, all of the moisture laden air must pass through or around the various sprays on the paper machine before finding an exit through the pipe 30, with the result that substantially all of the moisture is 70 condensed out and removed. Any moisture condensing in the conduits 103 drains by gravity into the save-all 23.

The paper web 22 passes from the couch roll 13 onto the first press felt 35, through the first set of presses 36 and thence to the second press felt 37. After passing through the second set of presses 38, the direction of the web 14 is reversed and the web passed through the third set of presses 39, from 80 which it passes in a relatively dry state into the nip between the first bottom drier drum 40 and the lower drier felt 41 (Figure 3). The paper web 22 passes around the lower drier drum 40 and between the upper drier 85 felt 42 and first upper drum 43 and thence around the remaining upper and lower drum in the usual manner until it reaches the end of compartment A. Compartment A is divided from compartment B by means of 90 upper and lower partitions, 44 and 45 respectively, and seals 46 and 47 joined thereto. Said seals 46 and 47 may suitably comprise flexible metal plates 48 having rounded edges 49 and pivoted to a supporting plate 100 from the partitions 44 and 45 as at 50 and 51, respectively. The particular form and construction of the seals 46 and 47 form no part of the present invention.

The paper web 22 passes in a similar manner over and around the drier drums contained in compartment B and through a similar sealing mechanism, designated as a whole by the reference numeral 52 into compartment C. 105

Compartment C houses, in place of the usual drier drums, a system of high pressure steam coils 6 arranged in horizontal tiers. In order to support the paper web in spaced relation to the steam pipes or coils 6, plates 110 53 are supported above each tier of coils to extend between rolls 54 and 55, and similar pairs of rolls, positioned at the respective ends of the compartment C. The paper web may suitably be supported upon these horizontal 115 or slightly inclined plates 53 in their circuitous travel around the various rolls, such as the rolls 54 and 55, in their passage through compartment C. Each of the plates 53 may be formed of wire reinforced glass or any other suitable translucent material which will serve to transmit radiant heat.

From compartment C, the web is led through a seal, designated as a whole by the reference numeral 57, into a relatively small 120 125 130

compartment D in which are housed a plurality of steam drier drums 58. From the compartment D, the paper web passes out through a sealing mechanism 59 to the calender stack 7.

5 Compartment D may be operated as an outlying portion of section B or may be operated at its own peculiar pressure with its drums supplied with exhaust steam from any incidental source.

10 The arrangement of the drier sections will now be explained. High pressure steam is admitted to the pipes or coils 6 in compartment C through a pipe 60 and after traversing the various coils of the system, the condensate is discharged through a bottom pipe 61, which may suitably lead to a trap (not shown) for the removal of condensate, and whatever steam may inadvertently escape is 15 to be led by suitable connections (not shown) into pipe 62, thence to the driers 58 in the compartment D. In operation, the steam admitted to the coils 6 in the drying system of compartment C may be superheated and at a relatively high pressure, say 150 to 200 lbs. per sq. in. Heat radiated from the steam pipes 6 causes the evaporation of the moisture contained in the paper web, but at this heat is largely radiant heat, the paper 20 web is not necessarily raised to any high temperature corresponding with that of the steam in the coils and naturally this is so, as long as the paper web contains any moisture in it at all.

35 Under these conditions, the temperature of the paper web must remain at about the temperature of saturated steam corresponding with the pressure within the chamber C, although the web may be receiving radiant heat at short range having a temperature 40 100° or more higher than the aforesaid temperature. Under such conditions, the web is in danger of being overheated only should it come into contact with the high pressure 45 steam coils, but this is precluded by the provision of translucent plates between the steam coils and the traveling web of paper being dried.

There is thus produced an atmosphere of 50 dry steam within the casing C, which steam may or may not be superheated but is preferably kept under a super atmospheric pressure, the pressure being as high as it is practical to build the casing to withstand. The 55 steam thus generated from the moisture contained in the paper web is conducted from the upper portion of the compartment 5 through a conduit 62 to the drier drums in compartment B.

60 The conduit 62 may serve as a header to which the drier drums in section B are connected by means of individual pipes 63, or a part of the drier drums in said compartment B may be connected in series to the 65 conduit 62.

Steam generated from the web of paper as it passes through compartment B is conducted from said compartment by means of a pipe or conduit 64 and branch pipes 65 to the drier drums in compartment A. It is therefore necessary that compartment B be maintained under less pressure than compartment C and under greater pressure than compartment A. For instance, if compartment C is maintained under 30 lbs. gage pressure, compartment B might be maintained under a pressure varying from atmospheric to a few inches of vacuum and compartment A might be maintained under the highest vacuum practicable. By this arrangement, there is obtained in substance a multiple effect evaporation of the moisture or water contained in the paper web. Such construction with the accompanying multiple effect mode of operation develops fuel efficiency to 75 the maximum.

Compartment D constitutes a kind of equalizing chamber or lock between the high pressure compartment C and the atmosphere. A pressure relief valve 67 maintains a pressure within compartment D only slightly above atmospheric and from it steam generated from the paper web within said compartment may be conducted through a pipe 68 into the conduit 62 or into the conduit 64. Valves 69 and 70 are provided for controlling the disposition of the steam passing through the relief valve 67. Any other supplies of steam necessary to the operation of the driers 80 may be conducted to the suitable compartment through these same valves.

It should be noted that the arrangement of graduated pressures in the various compartments and of seals separating the compartments is conducive to a relaxation of the efficiency of the seals, such as is required in the types of vacuum drier now in use. The primary seal between the highest vacuum, viz. that in compartment A, and the atmosphere, is maintained by the valve 17 and the seal provided by the solid column of water or stock ahead of said valve 17. The seal 59, which is the only seal of appreciable dimension which connects the interior of the housing with the atmosphere, is subject to internal steam pressure from within the compartment D, so that whatever leakage may occur here flows outwardly constituting merely a loss of so much steam. Leakage through the seals between the various compartments cannot vitiate the maintenance of air-free vapor in casing C. Nor can leakage through the seals 46 and 47 into section A vitiate the vacuum therein, although such leakage may impose an extra load upon the vacuum pump 115 120 125 100.

The seals 46, 47, 52 and 57 merely seal vapor against vapor. If they leak, neither steam heat nor vacuum is lost thereby but merely a fractional availability of the steam 130

with resultant loss of slight fuel efficiency. The steam leakage past the seal 59 may take the place, in part, of the usual sweat rolls, which serve to recondition the paper after 5 being dried.

Such a construction as above described would develop fuel efficiency to the maximum, consuming theoretically only about one-third of the steam consumed by known 10 types of vacuum driers now in use, or about one-quarter of the steam consumption of the usual type of open driers. Furthermore, the incidental operative cost, as for vacuum pump, power, and the like, would be not more 15 and probably less than the corresponding cost in the operation of the present type of vacuum driers. The size and initial cost of a machine of my invention, however, would be relatively large as compared with the 20 present type of vacuum drier, owing to the necessity for using more drier drums and the enclosing of the entire paper machine rather than the drier unit only.

As shown in Figure 7, one or more of the 25 compartments of the drier unit, such as the compartment D, may be provided with means for circulating air through the drier compartment and with means for reutilizing the heat of the exit air and gases, which otherwise would be lost, in the preheating of the air admitted to the compartment.

For this purpose, a fan or blower 105, having an intake pipe 106, is connected by means 30 of a discharge pipe 107 through a heat interchanging air regenerating device 108 to the compartment D, preferably to the lower portion 35 of said compartment as at 109. Another pipe 110 leading from near the top of the compartment D, conducts the exit air and 40 gases from said compartment through the heat interchanging device 108 where a portion or all of the heat of the exit gases is given up to the incoming air. The gases are 45 finally discharged from the heat interchanging device 108 through a discharge pipe 111.

It will be understood that any conventional 50 type of heat interchanging device may be used for effecting the utilization of a portion of the heat contained in the exit gases from the compartment D for preheating the incoming air. By this arrangement, effective 55 air circulation can be maintained within the compartment D without resulting in a loss of heat values such as normally occurs in the open or unenclosed type of steam paper drier units. The compartment D will, of course, be maintained under substantially atmospheric pressure so that there will be no necessity for expensive sealing mechanism or 60 air-tight casing construction.

While the provision of air circulating and 65 heat interchanging means has been shown only in connection with a single compartment, it will be understood that other compartments may be similarly arranged. If

this same principle be applied to the entire machine and the machine enclosed but not provided with evacuating devices, with the air circulated through the casing in the manner described, then it is evident that such a 70 drier unit combines the features of the type of drier previously discussed wherein no fuel is wasted in heating air and also the advantage of economy in area of drier surface offered by the type of drier wherein the drier unit is composed of steam heated drums not enclosed within a casing. This modified 75 form of drier of my invention eliminates the waste of heat of the open type of drier unit and also the necessity of expensive apparatus 80 as required in the vacuum, enclosed type of drier unit.

I am aware that many changes may be made and numerous details of construction 85 may be varied through a wide range without departing from the principles of this invention, and I, therefore, do not purpose limiting the patent granted hereon otherwise than necessitated by the prior art.

I claim as my invention:

1. The combination with a paper machine, 90 of a substantially air-tight housing therefor completely enclosing both the wet and dry ends thereof.

2. The combination with a paper machine, 95 of a housing therefor completely enclosing both the wet and dry ends thereof, said housing being divided into compartments and means sealing said compartments from each other and from the outside.

3. The combination with a paper machine, 100 of a housing therefor completely enclosing both the wet and dry ends thereof, suction means connected to the interior of said housing for putting said wet end under a vacuum and means permitting the flow of stock to said wet end and compelling the flow of white water therefrom.

4. In a completely enclosed paper machine, 105 a housing section enclosing the wet end of the machine and some of the driers.

5. In a completely enclosed paper machine, 110 a housing section enclosing the wet end of the machine and some of the driers and means for creating a vacuum within said housing section.

6. In a completely enclosed paper machine, 115 a housing section enclosing the wet end of the machine and some of the driers and means including a vacuum pump connected to flat suction boxes and a suction couch roll of the machine for creating a vacuum within said housing section.

7. In a paper machine, a sectional housing 120 enclosing the dry end thereof, heating means in the compartments of said housing so formed and means for leading steam generated from the moisture contained in the paper from one section to the heating means of a 125 compartment of lower pressure.

8. In a paper machine, a sectional housing enclosing the dry end thereof, heating means in the compartments of said housing so formed, means for leading steam generated 5 from the moisture contained in the paper from one section to the heating means of a compartment of lower pressure and means sealing the compartments from each other to permit the passage of paper therethrough.
10. 9. In a paper machine, a sectional housing enclosing the dry end thereof, heating means in the compartments of said housing, means for leading steam generated from the moisture contained in the paper from one compartment to the heating means of a compartment of lower pressure, means sealing the compartments from each other to permit the passage of paper therethrough and means for maintaining said compartments under different pressures.
15. 10. In a paper machine, a sectional housing therefor forming compartments and means for maintaining said compartments under different pressures ranging from sub-atmospheric at the wet end to super-atmospheric towards the dry end.
20. 11. In a paper machine, a sectional housing therefor forming compartments, means for maintaining said compartments under different pressures ranging from a lower pressure at the wet end to a higher pressure towards the dry end, heating means within the compartments of the dry end and means for conducting steam generated from the moisture contained in the paper from one compartment to the heating means in a lower pressure compartment.
25. 12. In a paper machine including a Fourdrinier section, a press section and a drier section, a housing completely enclosing the paper machine, partitions and seals dividing said housing into compartments, one compartment enclosing the fourdrinier, press section and a group of driers, other compartments enclosing groups of drying elements, and means for maintaining said compartments under contrasted degrees of pressure.
30. 13. In a paper machine including a Fourdrinier section, a press section and a drier section, a housing completely enclosing the paper machine, partitions and seals dividing said housing into compartments, one compartment enclosing the fourdrinier, press section and a group of driers, other compartments enclosing groups of drying elements, means for maintaining said compartments under contrasted degrees of pressure and means for conducting steam generated in a higher pressure compartment to drying elements in a lower pressure compartment.
35. 14. In a paper machine including a forming portion and a drier, a housing completely enclosing the forming portion and drier, partitions and seals between groups of the drying elements permitting the passage of the paper web through the compartments thus formed, the drying elements in one such compartment comprising high pressure steam coils.
40. 15. In a paper machine including a forming portion and a drier, a housing completely enclosing the forming portion and drier, partitions and seals between groups of the drying elements permitting the passage of the paper web through the compartments thus formed, the drying elements in one such compartment comprising high pressure steam coils and means for conducting steam generated from paper passing through said one compartment to drying elements in a compartment of lower pressure.
45. 16. In a paper machine, a sectional housing therefor, high pressure steam coils in one section thereof and translucent means for supporting the paper web adjacent to but spaced from said coils.
50. 17. In a paper machine, a sectional housing therefor, high pressure steam coils in one section thereof, means for supporting the paper web adjacent to but spaced from said coils, drier drums in another section of said housing and means for conducting steam generated from the paper web in the one section into said dried drums.
55. 18. In a paper machine, an enclosed drier section from which air is substantially excluded, partitions and seals dividing said drier section into a plurality of compartments, heating elements in each compartment and means for maintaining said compartments under graduated pressures.
60. 19. In a paper machine, an enclosed drier section from which air is substantially excluded, partitions and seals dividing said drier section into a plurality of compartments, heating elements in each compartment, means for maintaining said compartments under graduated pressures ranging from sub to super atmospheric toward the dry end and means for leading steam generated from moisture in the paper in a higher pressure compartment to the heating elements in a lower pressure compartment.
65. 20. In a paper machine, an enclosed drier section from which air is substantially excluded, partitions and seals dividing said drier section into a plurality of compartments, heating elements in each compartment, means for maintaining said compartments under contrasted pressures graduated from sub to super atmospheric toward the dry end, high pressure steam coils in a superatmospheric compartment and means leading steam generated from moisture in the paper in said superatmospheric compartment into a preceding lower pressure compartment.
70. 21. In a paper machine, an enclosed drier section from which air is substantially excluded, partitions and seals dividing said drier section into a plurality of compartments.

ments, heating elements in each compartment, means for maintaining said compartments under contrasted pressures graduated from sub to super atmospheric toward the dry end, 5 high pressure steam coils in a superatmospheric compartment, steam drier drums in a preceding sub-atmospheric compartment and a conduit leading steam generated from moisture in the paper web in said superatmospheric compartment into said drier drums.

22. In a Fourdrinier paper machine including a wet and dry end, a substantially air tight casing completely enclosing said wet and dry ends and sealing means at the ends 15 of said casing against the admission of air thereinto.

23. In a Fourdrinier paper machine including a wet and dry end, a substantially air tight casing completely enclosing said wet 20 and dry ends, sealing means at the ends of said casing against the admission of air thereinto and means for creating contrasted degrees of pressure within said casing.

24. In a Fourdrinier paper machine including a wet and dry end, a substantially air-tight casing enclosing the entire machine, partitions and seals dividing said casing into compartments, one compartment enclosing the wet end and a portion of the driers in the 30 dry end, and means for partially evacuating said compartment.

25. In a Fourdrinier paper machine including a wet and dry end, a substantially air-tight casing enclosing the entire machine, 35 partitions and seals dividing said casing into compartments, one compartment enclosing the wet end and a portion of the driers in the dry end, means for partially evacuating said compartment, another compartment enclosing a portion of the drier drums, means for maintaining a lesser vacuum in said second compartment and means conducting steam generated from moisture contained in paper in said second compartment into the 40 drier drums of said first compartment.

26. A paper machine including a Fourdrinier having flat suction boxes and a suction couch roll, comprising a substantially air-tight casing for said machine, a vacuum 50 pump, a branched intake thereto connected in parallel to said suction boxes, couch roll and to the wet end of said casing and a constant pressure difference valve in the connection leading from said pump to wet end of 55 said casing.

27. A paper machine, a substantially air-tight casing therefor, including the wet end and a portion of the driers, a vacuum pump and a conduit connecting the intake of said 60 pump to the wet end of said casing.

28. A paper machine, a substantially air-tight casing therefor, driers therein at the dry end of the machine for evaporating the moisture from the paper web and means for 65 conducting the vapor thus formed into heat

exchanging contact with the wet end of the machine.

29. A paper machine, a casing therefor, driers at the dry end thereof for evaporating moisture from the paper web, a head box 70 for incoming stock and conduits traversing said head box opening at their ends near the top and bottom of said casing to drain condensate into the bottom of said casing.

30. In a paper drier, a casing enclosing all 75 or a part of the drier rolls, a heat interchanging air regenerator, and a fan blowing air through said regenerator into said casing at substantially atmospheric pressure, and then out of said casing through said regenerator again, to impart its heat to the incoming air.

In testimony whereof I have hereunto subscribed my name at Nyack, Rockland County, N. Y.
